UNITED STATES PATENT OFFICE.

LOUIS A. HAUCK, OF CINCINNATI, OHIO.

SWITCH FOR ELECTRIC TOOLS.

967,190.

Specification of Letters Patent. Patented Aug. 16, 1910.

Application filed January 27, 1908. Serial No. 474,508.

To all whom it may concern:

Be it known that I, LOUIS A. HAUCK, a citizen of the United States of America, and resident of Cincinnati, county of Hamilton, State of Ohio, have invented certain new and useful Improvements in Switches for Electric Tools, of which the following is a specification.

This invention relates to electric switches 10 and particularly to switches which are adapted to be used on portable tools or machines.

An object of this invention is the production of an electric switch which is particularly adapted to be mounted on portable 15 tools or machines and which is provided with means for insuring that the switch is always either fully opened or closed.

It is essential in portable tools that the 20 operating switch be mounted in a place convenient to the hand of the operator, and that it be so constructed that the tool may be stopped or started by a slight pressure of the finger or thumb of the operator. These 25 switches are ordinarily so constructed that the operator through carelessness may not fully open or close the switch or may move too slowly, and may thereby cause injury to the switch itself or to the tool by the arcing which, under such condition, may take place 30 between the terminals of the switch. In overcoming this defect of construction, I have made a switch which may be mounted on a convenient and protected portion of the tool and which is provided with a simple 35 operating device located on the handle of the tool and provided with means for preventing the switch from being left either partially opened or partially closed, by the negligence of the operator.

40 The arrangement of the apparatus embodying my invention is such that after an operator has moved the switch to partially open or close it, the operating device will either continue the motion quickly, or return 45 the switch to its former position, and thereby either fully open or close it.

Referring to the drawings accompanying this application and forming part thereof: Figure 1 is a partial side elevation and partial 50 sectional elevation of a switch embodying my invention and is shown in connection with a fragmental section of a portable tool or machine. Fig. 2 is a sectional view along line A—A of Fig. 1 and discloses the construction of the switch proper.

A handle, 3 is provided on the shell por-

tion 4 of a portable tool, or machine. The operating switch 5 of the machine is mounted within the shell portion 4 and consists of a fiber or other insulating plug 6 which is 60 inclosed by an insulating casing or housing 7 on the opposite sides of which spring terminals 8 and 9 are mounted. Each spring terminal is connected to a terminal wire 10 of the operating circuit of the tool or machine. 65

The plug 6 is adapted to move longitudinally of the casing 7 and carries a metallic contact piece 11 which, for a certain position of the plug 6 contacts with terminal tips 12, 70 one of which is provided on the free end of each terminal. Each spring terminal is secured to the insulating casing 7 by means of screws, or rivets 13 and so arranged that its tip 12 extends through an opening in the 75 casing 7 and contacts with an inclined face 14 of the plug 6. The contact piece 11 extends through the plug 6 and is located at the widest portion of the plug. By moving the plug outwardly, relative to the casing 7, the contact tips 12 are moved outwardly by the inclined faces 14 and the spring terminals are thereby put in tension. When the plug has been moved a predetermined amount, the contact piece 11 contacts 85 with and completes the circuit between the terminal tips 12, the tension of the spring terminals insuring a perfect contact. By moving the plug in the opposite direction, the circuit is broken between the tips 12 and 90 the switch is opened.

The operating mechanism for the switch consists of a thumb or finger lever 16 which is mounted on the handle portion 3 of the machine and which is connected to the plug 95 6 by means of a rod 17. The piece 16 is so mounted in the handle 3 that it presents each end to the hand of the operator, and is capable of moving longitudinally to shift the fiber plug 6 either to the open or the 100 closed position. A casing 18 is provided in the handle portion 3 and incloses the plunger 19 which is forced outwardly by a coiled spring 20 located within the casing and behind the plunger. A lug 21 is provided on the outer end of the plunger 19 and is adapted to contact with one or the other oppositely inclined faces 22 and 23, which are provided on the piece 16. The lug 21 is forced against one or the other of these 110 faces by the coiled spring 20 and the arrangement is such that it will slide down

one of the inclined surfaces, move the piece 16 and, consequently move the plug 6 to such a position as will either fully open or close the switch 5.

5 In the drawings the switch and the operating mechanism are shown in the fully open position. In moving the plug, 6, to close the switch, the thumb piece 16 is moved in the direction of the arrow, shown in Fig. 1 and the lug 21 is caused to slide up the inclined face 23 and then down the face 22. If, for any reason the operator does not move the piece 16 far enough to carry the apex of the inclined faces 22 and 23 past the 15 plug 21, the spring 20 will, by forcing the plunger 19 outwardly, cause the lug 21 to travel, relatively of the piece 16, down the inclined face 23, and thereby move the plug 6 to its previous position. If, however, the 20 piece 16 is moved to such a position that the apex of the inclined faces passes the lug 21 then the spring 20 will operate to force the lug 21 quickly down the inclined face 22 and to thereby move the plug 6 to the fully 25 closed position of the switch. By this arrangement the switch will so adjust itself that it is yieldingly locked in either the fully opened or fully closed position and it cannot occupy an intermediate position.

30 In accordance with the patent statutes I have illustrated and described what I now consider to be the preferred embodiment of my invention, but I desire to be understood that various modifications and changes may 35 be made in the apparatus without departing from the spirit or scope of this invention.

What I claim is:

1. An electric switch for portable electric tools comprising terminals and a movable 40 contact piece for making and breaking the circuit between the terminals, said terminals and contact piece being mounted in a protected position on the body of the tool, a thumb-piece capable of reciprocation, and

spring pressed means adapted to carry the 45 thumb-piece from an intermediate position to one or the other of its extreme positions, said thumb piece and spring pressed means being mounted upon the handle of the portable tool, and means for connecting the 50 thumb-piece and the contact piece.

2. An electric switch for portable electric tools, comprising an insulating shell mounted on a protected portion of the body of the tool, spring terminal pieces mounted 55 on said shell, a reciprocal insulating plunger within said shell, a contact piece carried by said plunger and adapted to make and break the circuit between said terminal pieces, and an operating device for said switch comprising a reciprocal thumb piece mounted on the handle portion of the tool, spring pressed means mounted in the handle portion for carrying the thumb piece from an intermediate position to one or the other of its 60 extreme positions and means secured to said thumb piece and said insulating plunger, for actuating said plunger.

3. In a switch for electrical tools the combination of a shell portion of a portable tool, a hollow tool handle secured in the shell portion, terminals mounted upon the interior of the shell portion, a movable contact piece upon the interior of the shell portion and adapted to make and break the 70 circuit between the terminals, a thumb piece projecting through the handle, a spring pressed means within the handle adapted to carry the thumb piece from an intermediate position to one or the other of its 75 extreme positions and a rod secured to the contact piece and engaging the thumb piece at a point upon the interior of the handle.
